UNITED STATES PATENT OFFICE

150,027

DESIGN FOR A BROOCH OR SIMILAR ARTICLE

Grayce Norato, Providence, R. I.

Application October 25, 1946, Serial No. 134,246

Term of patent 3½ years

(Cl. D45—19)

To all whom it may concern:

Be it known that I, Grayce Norato, a citizen of the United States of America, residing at Providence, county of Providence, State of Rhode Island, have invented a new, original, and ornamental Design for A Brooch or Similar Article, of which the following is a specification, reference being had to the accompanying drawing, forming a part thereof:

Fig. 1 is a plan view showing my new design for a brooch or similar article; and

Fig. 2 is a side elevation thereof.

The dominant part of the design is shown in full lines.

I claim:

The ornamental design for a brooch or similar article, substantially as shown and described.

GRAYCE NORATO.
